CLAIM

The ornamental design for a telephone line video data transmitter, as shown and described.

DESCRIPTION

FIG. 1 is a perspective view of the telephone line video data transmitter embodying the design of the present invention;

FIG. 2 is a front elevational view thereof;

FIG. 3 is a rear elevational view thereof;

FIG. 4 is an end elevational view thereof;

FIG. 5 is an end elevational view thereof;

FIG. 6 is a top plan view thereof; and,

FIG. 7 is a bottom view thereof.

The phone card has been shown broken away in FIGS. 1, 2, 4, and 5 for convenience of illustration.

FIG. 1

FIG. 2

FIG. 3

FIG. 4

FIG. 5

FIG. 6

FIG. 7
